UNITED STATES PATENT OFFICE.

EDWARD O'MALLEY AND EDWARD W. O'MALLEY, OF CHICAGO, ILLINOIS.

HEATER FOR ENGINES.

Application filed April 11, 1925. Serial No. 22,264.

Our invention relates to heaters for internal combustion engines.

The object of the invention is to provide an electrical heating device of simple and efficient construction adapted to be applied in an effective manner and location to a part of the water circulating jacket of an internal combustion engine and connected to an external source of electricity whereby the water in the circulating system of the engine may be heated for the purpose of warming the motor preliminary to starting the same. The electric heater is adapted to be connected to a source of electricity in the garage in which the motor vehicle may be stored or a shop or dwelling in which a stationary engine may be mounted. Another object of the invention is to provide a container or heater for the carrier which may be readily applied to that part of the water jacket of the engine adjacent the combustion chambers of the cylinders to thereby obtain a prompt and effective application of heat to that portion of the engine where it is most needed for the warming of the fuel in order to enable the initial explosions of the motor to be facilitated.

Another object of the invention is to provide a heating device in which means are provided for imparting the initial heating action of the heater to only a small quantity of water whereby the water may be quickly heated and providing means whereby the continued heating of the remaining body of water in the circulating system is gradually brought in contact with the heater solely by the circulation produced by the natural flow of the heated water in a rising column, with the colder water replacing the heated water as the latter flows from the heater.

With these objects and others in view, the invention is embodied in preferable form in the construction hereinafter described and illustrated in the accompanying drawings, in which drawings—

Fig. 1 is a vertical section through a part of an internal combustion engine showing the improved heater applied thereto;

Fig. 2, a horizontal section on the line 2—2 of Fig. 1; and

Fig. 3, a vertical section on the line 3—3 of Fig. 1.

The device may be applied to any internal combustion engine having a water jacket. In the particular engine herein illustrated,

1 designates the combustion space of a cylinder of an internal combustion engine, 2 the spark plug and 3 that portion of the water jacket chamber which is immediately 60 adjacent the combustion space and near the spark plug. In our invention, the heater shell or container is adapted to be mounted in an opening through the wall of the water jacket portion 3, which opening may be the 65 usual core opening formed in engines of many types or may be an opening specially drilled in the water jacket. In the preferable structural embodiment of the invention, a pipe section 4 is provided which is threaded into the opening of the wall of the water jacket chamber 3 and bears tightly at its outer end against a shoulder formed on a threaded flange 5 of the main shell 6 of the container. A threaded coupling nut 7 serves 70 to clamp the body of the shell to the pipe section 4. The main body of the shell is substantially circular in outline and has a water containing chamber 8 which depends below the level of the pipe section 4 and the portion 3 of the water jacket to which the device is applied. A horizontal bridge wall 9 is formed in the pipe section 4 and registers with a similar horizontal bridge wall or partition 10 formed in the main body of 85 the shell 6 and which wall 10 is curved downwardly within the body of the shell and extends past the center of the latter. This horizontal partition 10 has an opening in the center in which closely fits the walls of a 90 heat radiating member or casing 11 of an electric heater. The outer end of this casing is provided with a flange 12 which bears upon and is secured to a corresponding flange of the shell 6, the outer end of the 95 casing being closed by a plate 13. The plate 13 carries contact posts 14 which are electrically connected with an electric resistance and heating element 15 entirely inclosed within the heat radiating casing 11 of the 100 heater. At the lowest point of the chamber 8, the body of the container is provided with an outlet pipe 16 controlled by a draincock 17 whereby the water may be drained from the container when desired and in order to 105 prevent freezing.

In the use of the device, a connecting plug, having connection with a suitable source of electricity, is connected to the posts 14 to establish a circuit through the electric heating unit. The water in the chamber 15 of the shell surrounding the radiating casing of the 110

heater will be raised in temperature as the current flows through the heater causing the heated water to rise in the container. This heated water will pass out through the container above the partition and bridge wall 10, 9 into the water jacket adjacent the combustion chamber, inducing a circulation which will cause the colder water to flow from the lower part of the water jacket into the walls 9 and 10 of the lower part of the chamber 8 from whence it arises past the outer end of the downwardly curved wall 10 up against the heater, thus continuing the circulation until the water in the water jacket adjacent the combustion chamber has been heated and until the walls of the cylinder have been warmed sufficiently to facilitate the explosion of the fuel mixture.

The arrangement above described insures a prompt and effective heating of the water since the heating element is surrounded by only a small quantity of water and the circulation of the cooler water thereto takes place in a gradual flow directed and controlled by the bridge wall 10. This bridge wall also acts as a brace for the sides of the casing of the heating unit.

Having thus described our invention, what we claim is:

20 1. In a heater for water jackets and the

like, a pipe section adapted to be threaded into an opening in the wall of a water jacket or the like, a locknut for securing the pipe section in place, a horizontal partition in said pipe section, a water container having an opening registering with the pipe section, means providing a swivelled connection between the container and the pipe section, a forked partition in said container adapted to register with the partition in said pipe section, a cup-like closed casing with an opening at the outside of said container, said casing fitting in an opening in the container and also fitting between the forks of said partition, and electric heating means in the casing. 45

2. A heating appliance comprising a container for liquid, a casing projecting into the container to provide therewith a liquid chamber of substantially uniform cross-section, an electric heating element in the casing, a passage for connecting the container to the interior of a water jacket or the like, and a forked partition in said passage abutting against the casing and partially surrounding the same, substantially as set forth. 55

In testimony whereof we affix our signatures.

EDWARD O'MALLEY.
